UNITED STATES PATENT OFFICE.

JOHN H. FRANCIS, OF CLEVELAND, OHIO, ASSIGNOR TO THE KILBY MANUFACTURING COMPANY, OF CLEVELAND, OHIO, A CORPORATION OF OHIO.

WIRE-NAIL MACHINE.

979,457.

Specification of Letters Patent. Patented Dec. 27, 1910.

Application filed April 15, 1908. Serial No. 427,177.

To all whom it may concern:

Be it known that I, JOHN H. FRANCIS, a citizen of the United States, residing at Cleveland, in the county of Cuyahoga and State of Ohio, have invented a certain new and useful Improvement in Wire-Nail Machines, of which the following is a full, clear, and exact description, reference being had to the accompanying drawings.

10 This invention relates to machines for making wire nails and has for its object to improve the operation of the feeding mechanism whereby the wire is advanced toward the anvil and particularly to the arrangement and construction of such mechanism whereby the feeding movement of the wire will positively cease at a certain point before the engagement of the cutters therewith, notwithstanding the fact 20 that the machine is being operated at high speed.

In various other machines of this type with which I am acquainted, that is, machines wherein a crank is employed to operate the feeding mechanism, the parts have been so constructed that the wire was fed or advanced by the rearward movement of the crank and released by tripping the gripping mechanism before the crank reached 30 its rear center. When the machines thus constructed were running at high speed, there was irregularity in the lengths of the nails, due to inability to release the wire at the same point of the stroke. By my construction and arrangement of parts, the wire is released always at the same point and is advanced and released within an angular movement of 150 degrees or less of the drive or crank shaft from its front 40 center, thereby insuring uniformity in the lengths of the nails and preventing the cutting knives from engaging the wire until after its forward movement has been completed. I accomplish these results by means 45 of comparatively simple and inexpensive mechanism which will be described herein-after.

Generally speaking, the invention may be defined as consisting of the combinations of 50 elements embodied in the claims hereto annexed and illustrated in the drawings forming part hereof, wherein—

Figure 1 represents a plan view of a machine having my invention applied thereto; Fig. 2 represents an enlarged plan view

of my mechanism and of the co-acting parts of the machine; Fig. 3 represents a side elevation of the construction illustrated in Fig. 2; and Fig. 4 represents a somewhat diagrammatic view illustrating the movements of the feeding mechanism by the rotation of the crank shaft.

Referring to the drawings by reference characters, 1 denotes the bed plate of a wire-nail machine, the same being supported by 60 means of brackets 2.

3 denotes the anvil block having a longitudinal aperture 4 therethrough for the passage of the wire. The anvil block is provided in the rear face thereof with a die 5 carrying the holding dies 6 and 7. Holding die 7 has a pair of operating rods 8 and 9 connected thereto, the former having its outer end operatively engaged by a screw 10 extending through the forwardly 70 projecting arm of an angle lever 11 mounted on a vertical pivot 12. Rod 9 extends across the said arm of lever 11 and has a screw 13 threaded therethrough and bearing against the outer face of such lever arm. 80 The inwardly projecting arm 11^a of lever 11 is connected to a rock shaft 14 by means of a connecting rod 15. 11^b denotes a rearward extension of lever 11 which is engaged by a spring 16 tending to force the front 85 end of said lever outwardly. Rock shaft 14 is mounted in suitable bearings in brackets 17 and is provided with a rearwardly projecting rock arm 18 having at the rear end thereof a fork for the reception of a roller 90 19 which rests upon a cam 20 carried by the main shaft 21. This shaft is provided with a suitable drive pulley 22 at one end thereof and with a fly wheel 23 at the opposite end thereof and is mounted in suitable 95 bearings carried by bed plate 1. Near the middle portion thereof, shaft 21 is provided with a reciprocating device, preferably a center crank 24, which is connected by a suitable pitman 25 with the hammer stock 26. This stock is provided at the front end with the heading punch 27 and intermediate of its ends with oppositely-projecting lateral lugs 28 each having a roller 29 there-in adapted to engage the inwardly curved 100 rear ends of the cutting levers 30. These levers are mounted on vertical pivots 31 and are each provided with an adjustable cutter 32.

In front of anvil block 3 there is mounted 110

the feed block 33. This block is mounted on an inwardly projecting arm 34 and comprises a pair of vertical rollers 35 each mounted upon a rearwardly and outwardly inclined surface 36. The wire is gripped between the rollers 35 and a flat plate 37, the arrangement being such that, as the feed block moves toward the anvil block, the wire will be gripped by reason of the rollers 5 moving inwardly on the inclined surfaces 36 and will be released when such movement of the feed block is reversed by the movement of the rollers outwardly on said inclined surfaces. Arm 34 is mounted on a 10 block 38 which is longitudinally slideable 15 upon bed plate 1.

For the purpose of operating the feed block, I provide the following construction: 20 shaft 39 denotes a transversely extending rock shaft which may be mounted in bearings on bed plate 1. This shaft projects inwardly 25 beyond the hammer stock 26 and is provided, beneath said hammer stock, with a rearwardly projecting lever arm 40 rigid therewith. This arm is flexibly connected 30 with hammer stock 26 by means of a link 41 which is pivotally connected at one end to a pair of downwardly projecting lugs 42 on the hammer stock and at its opposite end to the rearwardly projecting end of lever arm 40. At its outer end, shaft 39 is provided 35 with an upwardly projecting lever arm 43 which is connected to arm 34 by means of a link rod 44. In order to vary the effect 40 of lever arm 43 on the feed block and thereby accommodate the feeding mechanism to various lengths of nails, the rear end of link rod 44 is connected to arm 43 by means of a sliding block 45 mounted in a vertically 45 extending guideway 46 in arm 43, said block being provided with an adjusting screw 47 whereby its position in the said guideway 50 may be varied.

In the full-line position illustrated in Fig. 45 4, the parts are shown in the positions which they occupy when crank 24 is at or near its foremost position. In Figs. 2 and 3, the parts are shown in the positions which they occupy when the crank is in front of its 50 shaft but not at its front center.

With the parts arranged and constructed as described thus far, it will be apparent that, as the crank moves from the rear center to the front center, the hammer 26 will 55 be moved forward and the heading punch will head the wire which has been fed through the holding dies 6 and 7, the rotation of shaft 21 causing the die-pushing rod 8 to force die 7 inwardly and grip the wire 60 firmly against the opposing die 6 before the engagement of the punch with the wire. The reverse movement of the shaft causes link 41 to pass from the forwardly inclined 65 position shown in Fig. 4 to the substantially vertical position shown in dotted lines in

said figure, rocking shaft 39 and moving the feed block 33 rearwardly. By the arrangement to be described more particularly hereinafter, this feeding movement ceases before the cutters 32 are forced against the wire by the engagement of rollers 29 with lever arm 30. Meanwhile, the elevated part of cam 20 has moved from beneath roller 19, and spring 16 has moved the front end of lever 11 outwardly, thereby pulling the holding die outwardly through rod 9 and permitting the feeding of the wire by the feed block. At the end of the rearward stroke of the hammer stock, when the crank 21 reaches its rear center, rollers 29 force the rear ends of the levers 30 outwardly, causing the cutters 32 to sever the headed wire which has been fed through the anvil block. 75 80 85

The manner in which the feeding of the wire is suspended a sufficient time before crank shaft 24 reaches its rear center to prevent any movement of the wire after the engagement of the cutters therewith will now be explained with particular reference to Fig. 4. In this view, the full lines indicate the positions assumed by the parts when the crank shaft is on its forward center and the dotted lines the center lines of the pitman, lever arms 40, 43 and link 41. When crank shaft 21 is on its forward center, link 41 makes a considerable angle with a vertical line passing through its point of connection with arm 40 and arm 43 also makes an appreciable angle with a vertical line drawn through its rock shaft 39. When the crank is on its rear center, arm 40 is in the position shown by the dotted line *a*, arm 43 is in the position shown by dotted line *b* and link 41 is in the position shown by dotted line *c*, which forms a very slight rearward angle with a vertical line *d* extending upwardly from the rear end of arm 40. Line *e* is a line which extends upwardly and forwardly from the rear end of line *a* and forms an angle with line *d* equal to the angle formed by line *c*. The distance between lines *c* and *e* along the line which extends rearwardly from the upper pivot of 95 100 105 110 115 120 125 130 135 140 145 150 155 160 165 170 175 180 185 190 195 199 200 201 such position, the oscillation of the arm 40 and arm 43 while the link 41 is oscillating between *a* and *c* is negligible. In fact, such oscillation will be easily compensated for by 5 the lost motion between the parts and the lines *a* and *b* represent the positions maintained by arms 40 and 43 respectively while link 41 is moving between *e* and *c*. The result is that the rearward movement of arm 10 43 and consequently the rearward or feeding movement of the feed block is suspended for a material interval of time both before and after the crank passes its rear center, affording ample opportunity for the cutting of 15 the ends of the wire by the cutters after the cessation of the feeding movement of the wire, no matter at how high a speed the machine may be operated.

As will appear from Fig. 4, arms 40 and 20 43 are at nearly right angles to each other, the angle therebetween being about 96 degrees, which I have found, with the other parts arranged as shown, will secure the results described herein.

25 I claim:

1. In a machine of the character set forth, the combination of a feed block, a shaft, a member connected with said shaft and movable thereby toward and from said feed 30 block, a rock shaft having a pair of arms, a connection between one of the arms of said rock shaft and the feed block, and a link connecting the movable member with the other arm of said rock shaft, the parts being arranged so that said link is in a substantially vertical position when said movable member is at or near one end of its stroke.

2. In a machine of the character set forth, 40 the combination of a shaft, a feed device, and connections between said shaft and said device, said connections comprising a member connected to the shaft to be reciprocated thereby, a bell crank lever having one arm 45 extending substantially parallel with the direction of movement of said member and having its other arm extending at substantially right angles to the other arm, a link connecting the other arm to said member, 50 and a link connecting the latter arm to the feed device.

3. In a machine of the character set forth, the combination of an anvil block, a shaft, 55 a feed block, and connections between said shaft and said feed block, said connections comprising a member connected with the shaft and reciprocable toward and from the anvil block, a rock shaft having thereon a pair of arms arranged at substantially right 60 angles to each other, one of said arms being substantially parallel with the direction of movement of said member, a link connected with the latter arm and with the movable member and arranged to be in a position at 65 substantially right angles to the direction of

movement of said member when said member is in its most remote position from the anvil block, and a connection between the other arm of said lever and the feed block.

4. In a machine of the character set forth, 70 the combination of an anvil block, a feed block on one side of said anvil block, a shaft on the other side of said anvil block, a member connected with said shaft and reciprocable thereby in a horizontal direction toward and from the anvil block, a rock shaft having a pair of arms connected thereto and extending at substantially right angles therefrom, one of said arms projecting rearwardly from said shaft and being substantially parallel with the direction of movement of said member and the other arm 75 extending in a vertical direction from said shaft, a link connecting the former arm to the movable member and arranged to be brought to a vertical position at a material period of time before the member is at its most remote position from the anvil block, 80 and a connection between the other arm and the feed block.

5. In a machine of the character set forth, 90 the combination of an anvil block, a feed block on one side of said anvil block, a crank shaft on the other side of said anvil block, a member connected with said crank-shaft 95 and reciprocable in a horizontal direction toward and from the anvil block, a rock shaft having a pair of arms connected thereto and extending at substantially right angles therefrom, one of said arms projecting rearwardly 100 from said shaft and being substantially parallel with the direction of movement of said member and the other arm extending in a vertical direction from said shaft, a link connecting the former arm to the movable member and arranged to be brought to a vertical position at a material period of time before 105 the crank shaft passes the center remote from said anvil block, and a vertically adjustable connection between the vertical arm 110 and the feed block.

6. In a machine of the character set forth, 115 the combination of a feeding device, a shaft, a member connected with said shaft and movable thereby in a generally horizontal direction toward and from the feeding device, a rock shaft having a pair of arms, a connection between one of the arms of said rock shaft and the feeding device, a link connecting the movable member with the other arm of said shaft, the parts being arranged so that said link is in a substantially vertical position when the movable member is at or near one end of its stroke, cutters 120 operated by the movement of said shaft, and connections whereby said cutters are operated to sever the wire after the link has reached a substantially vertical position.

7. In a machine of the character set forth, 130 the combination of a feeding device, a shaft,

a member connected with said shaft and movable thereby in a horizontal direction toward and from said feeding device, a rock shaft having a pair of arms, a connection 5 between one of the arms of said rock shaft and the feeding device, a link connecting the movable member with the other arm of said rock shaft, the parts being arranged so that the link is in a substantially vertical 10 position when said movable member is at or near one end of its stroke, a cutting device, and connections whereby said cutting device will be operated by the movable member to sever the wire after the said link has 15 reached a substantially vertical position.

8. In a machine of the character set forth, the combination of a feed block, a main shaft, an operating member movable by the

rotation of said main shaft toward and from the feed block, a member connected to 20 said operating member and reciprocable thereby, a rock shaft having a pair of arms, a connection between one of said arms and the feed block, and a link connecting the second member with the other arm of said 25 rock shaft, the parts being arranged so that the link is substantially at right angles to the throw of the operating member when the latter is at or near one end of its stroke.

In testimony whereof, I hereunto affix my 30 signature in the presence of two witnesses.

JOHN H. FRANCIS.
